UNITED STATES PATENT OFFICE

165,053

COMBINED SIGN AND TRELLIS

Arthur Crawford, Baltimore, Md.

Application May 15, 1951, Serial No. 15,187

Term of patent 14 years

(Cl. D1—12)

To all whom it may concern:

Be it known that I, Arthur Crawford, a citizen of the United States, residing at Baltimore (independent city), in the State of Maryland, have invented a new, original, and ornamental Design for a Combined Sign and Trellis, of which the following is a specification, reference being had to the accompanying drawing, forming part thereof.

Figure 1 is a front elevational view of a combined sign and trellis showing my new design;

Figure 2 is a side elevational view;

Figure 3 is a top plan view thereof; and

Figure 4 is a bottom plan view of the same.

I claim:

The ornamental design for a combined sign and trellis, as shown.

ARTHUR CRAWFORD.
